DESIGN FOR AN EMERGENCY PORTHOLE CLOSURE UNIT

Henry B. Cohen, New York, N. Y., assignor to
Sea Emergency Devices, Inc., New York County,
N. Y., a corporation of New York

Application December 2, 1943, Serial No. 111,873

Term of patent 14 years

(Cl. D71—1)

To all whom it may concern:

Be it known that I, Henry B. Cohen, a citizen of the United States, residing in the city, county, and State of New York, have invented a new, original, and ornamental Design for an Emergency Porthole Closure Unit, of which the following is a specification, reference being had to the accompanying drawing, forming a part thereof, in which:

Fig. 1 is a top plan view of an emergency porthole closure unit showing my new design; and

Fig. 2 is a rear view in perspective of said design.

I claim:

The ornamental design for an emergency porthole closure unit, as shown.

HENRY B. COHEN.
